UNITED STATES PATENT OFFICE.

LEONARD B. KRICK, OF CHICAGO, ILLINOIS, ASSIGNOR TO CITRUS PRODUCTS COMPANY, OF CHICAGO, ILLINOIS, A CORPORATION OF ILLINOIS.

DESIGN FOR A BOTTLE.

Application filed January 24, 1929. Serial No. 29,754. Term of patent 14 years.

To all whom it may concern:

Be it known that I, LEONARD B. KRICK, a citizen of the United States, residing at Chicago, Illinois, have invented a new, original, and ornamental Design for a Bottle, of which the following is a specification, reference being had to the accompanying drawing, forming part thereof.

The figure shown in the drawing is a front elevation of a bottle embodying the invention.

I claim:

The ornamental design for a bottle as shown.

LEONARD B. KRICK.
